UNITED STATES PATENT OFFICE.

WENDELEND L. EPHLIN, OF CHICAGO, ILLINOIS.

PACKAGE POCKET-GUARD FOR SHIPPING-BOXES.

1,361,318.

Specification of Letters Patent. Patented Dec. 7, 1920.

Application filed August 13, 1919. Serial No. 317,236.

To all whom it may concern:

Be it known that I, WENDELEND L. EPHLIN, a citizen of the United States of America, and a resident of Chicago, county of Cook, and State of Illinois, have invented 5 certain new and useful Improvements in Package Pocket-Guards for Shipping-Boxes, of which the following is a specification.

10 The main objects of this invention are to provide an improved pocket guard for shipping boxes adapted to support a comparatively fragile package and protect it against injury by the other and bulkier contents in 15 the shipping box; to provide an improved manner of forming said pocket guard; to provide an improved arrangement of attaching means on said pocket guard whereby the same may be easily and quickly secured 20 in place in the shipping box; and to provide an improved pocket guard of this kind which is particularly adapted to support, in boxes used for shipping butter or butter substitutes, packages filled with capsules 25 containing liquid coloring material.

An illustrative embodiment of this invention is shown in the accompanying drawings, in which—

Figure 1 is a plan of a piece of metal 30 showing the manner in which pocket guards are cut therefrom without waste of material.

Fig. 2 is a perspective view of the pocket guard ready for attachment in a shipping box.

35 Fig. 3 is a perspective view of a shipping box showing the pocket guard in place.

Fig. 4 is an enlarged sectional detail illustrating the manner in which the pocket guard is secured to the shipping box.

40 An application of this invention involves the use of a piece of metal bent to suitable shape so that when attached to the interior of a shipping box, it provides a pocket, the walls of which are sufficiently strong to protect 45 a comparatively fragile package against injury or destruction by the other contents of the shipping box. In the specific embodiment herein shown, the pocket guard 5 is formed of tin and is shown arranged in a 50 pulp board carton 6.

The member from which the pocket guard is formed is cut from a strip of material, as clearly indicated in Fig. 1, so as to provide a tongue 7 at one edge thereof, which results 55 in the formation of a notch or recess 8 in the

opposite edge. This member is bent so as to provide a side 9 offset from the plane of the flanges 10, disposed parallel to the side 9 and at substantially right angles to the ends 11. The tongue 7 is bent upwardly at right 60 angles to the side 9 so as to provide a bottom.

The flanges 10 have apertures 12 formed therein, which are adapted to receive fastening means such as brads or nails 13 65 which are retained in place by having tongues 14 bent over from the ends of the flanges 10 so as to bear against the heads of said brads.

The pocket guard 5 is secured within the 70 shipping box 6 against one side or end thereof by having the brads driven into the material from which the box is constructed. Where this material is made of pulp board, as shown in the drawings, the brads are 75 usually long enough so that the ends thereof are clenched over as shown in Fig. 4. The attachment of the pocket guard in this manner provides a pocket into which the desired package is placed, and the notch or recess 8 80 makes it possible to obtain a thumb or finger hold on the package so as to enable it to be readily removed from the pocket without removing the contents of the shipping box, if it is so desired.

85 The size of the pocket guard may, of course, be varied to accommodate any desired size or shape of package, and the material from which it is made will generally be determined by the protection which it is 90 desired to afford the package within the shipping box.

95 This pocket guard is particularly suitable for shipping liquid coloring matter with butter or butter substitutes. This coloring matter is usually placed in capsules, a number of which are placed in a small cardboard receptacle or package. Heretofore, it has been the practice to place these receptacles in one corner of the shipping box, with the 100 result that the butter or butter substitutes have pressed against the package containing the coloring capsules and compressed it so as to break the capsules or some of them, whereupon the coloring matter would 105 leak into the shipping box and discolor much of the contents. By providing a pocket guard of the kind herein shown and described, this difficulty is completely overcome in a very simple and effective manner 110

without consuming any additional space in the shipping box than would otherwise be required.

This guard also protects the capsule package from being affected by the moisture more or less present on or about the contents of the box, so that said package will not be softened or weakened and be more readily broken, as is frequently the case where the 10 capsule package is shipped loose in the box.

Although but one specific embodiment of this invention has been herein shown and described, it will be understood that details of the construction shown may be altered or 15 omitted without departing from the spirit of this invention as defined by the following claims.

I claim:

1. A device of the class described, comprising a piece of sheet metal formed with a notch extending inwardly from one edge, and a tongue protruding from the opposite edge which tongue is the complement of said notch, both being formed by the successive 20 cutting of devices from a strip of sheet metal, said member being bent so as to form a side, a pair of ends disposed at right angles to 25

said side, and flanges disposed at right angles to said ends, and means fixed on said flanges for securing said member to a side of a shipping box so as to provide a pocket adapted to receive a package, said tongue being bent at right angles to said side so as to form a bottom for said pocket. 30

2. A device of the class described, comprising a piece of sheet metal formed with a notch extending inwardly from one edge, and a tongue protruding from the opposite edge, said member being bent so as to form a side, a pair of ends disposed at right angles 35 to said side, and flanges disposed at right angles to said ends, said flanges having apertures formed therein, nails in said apertures, and tongues on said flanges bent over said nails to secure the same in said apertures, 40 said member being adapted to be secured to a side of a shipping box so as to provide a pocket adapted to receive a package, said tongue being bent at right angles to said side so as to form a bottom for said pocket. 45 50

Signed at Chicago this 11th day of August, 1919.

WENDELEND L. EPHLIN.
